UNITED STATES PATENT OFFICE.

LOUIS PHILIP PUTT, OF TORONTO, OHIO.

HAIR CURLER.

Application filed May 6, 1924. Serial No. 711,368.

To all whom it may concern:

Be it known that I, LOUIS PHILIP PUTT, a citizen of the United States, and a resident of Toronto, in the county of Jefferson and State of Ohio, have invented certain new and useful Improvements in Hair Curlers, of which the following is a specification.

This invention relates to hair curlers and 10 is more particularly adapted for curling locks of bobbed hair and also locks of long hair.

An object of the invention is the provision of a device having a pair of cooperating gripping members which are adapted to be readily bent to form a pair of opposed loops for receiving a lock of bobbed hair and which are adapted to be twisted onto the lock of hair for gripping the same so 20 that the curler may be turned to wind the lock of hair on the curler with the projecting ends of the curler being adapted for clamping the curler and lock against displacement.

25 A further object of the invention is the provision of a device not only adapted for curling locks of bobbed hair but for the purpose of curling long locks of hair with clamping members at the ends of the curler 30 about which the lock is adapted to be twisted for gripping the free end of the lock and also the opposite end of the lock adjacent the head after the lock of hair has been curled around the device.

35 This invention will be best understood from a consideration of the following detailed description, in view of the accompanying drawing forming a part of the specification; nevertheless it is to be understood that the invention is not confined to 40 the disclosure being susceptible of such changes and modifications which shall define no material departure from the salient features of the invention as expressed in 45 the appended claims.

In the drawings:

Figure 1 is a side view of the curler showing its adaptation for curling locks of bobbed hair.

50 Figure 2 is an elevation of the curler adapted for use in curling long locks of hair.

55 Referring more particularly to the drawings, the device consists of two flexible strands 1 and 2 which are of the same length and each strand may consist of a wire cov-

ered with a fabric casing. In fact the strands may be of a length of insulated copper wire such as used for electrical conductors. The strands may of course be 60 made of other material which has sufficient flexibility for accomplishing the purpose for which the curler is intended.

In forming the curler the strands are placed together in juxtaposition and the portions of the strands are rigidly locked together by metal bands 3 and 4. These metal bands are located sufficiently inward of the ends of the strands to provide pairs of freely movable clamping jaws 5, 6, 7 and 8 which are particularly useful in curling long strands of hair. The intermediate portions are ordinarily bent outwardly from each other to provide a pair of opposed arcuately shaped members 9 and 10 through 75 which the end of a lock of bobbed hair is adapted to be inserted and be gripped when the strands are twisted around each other as has been described in my allowed application, Serial No. 574,230, filed July 11, 80 1922.

The connected strands are ordinarily located in parallel relation and are firmly grasped by the fingers and pulled about one inch apart as shown in Figure 1 and to 85 form the opposed arcuate shaped members 9 and 10. The end of the lock of moistened hair is placed through the opening between the jaws 9 and 10 when the jaws are pressed towards each other to grip the hair. The 90 strands are then twisted in order to hold the end of the lock securely and the curler is then turned for winding the lock upon the same. When the limit of movement is reached the pairs of outer free ends 5, 6 95 and 7, 8 are bent inwardly and upon the lock for holding the curler and the hair wound upon the curler in position adjacent the head.

In employing the device for curling long locks of hair the ends 5, 6 and 7, 8 are spread apart, as shown in Figure 2. A lock of dampened hair is placed in the fork formed by the ends 5 and 6 when the members are pressed towards each other and clamped upon the lock adjacent the head. The lock is then wound or wrapped about the twisted strands and the end of the lock is then clamped between the jaws 7 and 8 at the opposite end of the curler.

100 After a sufficient length of time the curler 105 may be removed in either case.

What I claim is:

1. A hair curler comprising a pair of elongated flexible elements and spaced means for securing portions of the elements together remote from the ends of said elements to form an intermediate loop for clamping hair, with the outer ends of the flexible elements beyond the securing means being free and forming clamping jaws.
2. A hair curler comprising a pair of elongated flexible elements having metal bands for securing the elements together at

spaced points and located remotely from the ends of the elements, thereby providing a pair of intermediate clamping jaws ¹⁵ and pairs of end clamping jaws.

3. A hair curler comprising a pair of intermediate flexible clamping elements adapted to receive a lock of hair therebetween, and a pair of flexible clamping elements at each end of the intermediate clamping element.

LOUIS PHILIP PUTT.
